LAP STICK

James R. Wilson, Ramseur, N. C.

Application November 17, 1936, Serial No. 111,333

1 Claim. (Cl. 19—162)

This invention relates to an improved lap stick adapted for use in a lapper picker, intermediate picker, one process picker, carding machine, and in fact in any machine where a lap roll is formed or used in fibre preparation.

A lap roll in a lapper picker is usually formed on a hollow lap pin. When the lap is placed in other fibre preparation machinery such as intermediate pickers, or carding machines for example, the lap pin is removed but a lap stick remains in the lap roll for facilitating the handling of the lap roll, as in processing the same in subsequent machines, the lap stick serves as a stay or a guide for the lap roll and in machines such as intermediate pickers and carding machine the lap stick engages a suitable guide or standard to prevent bodily movement of the lap roll as the lap is drawn therefrom.

Lap sticks heretofore have been provided for the insertion in the lap pins so that the lap pin can be removed from the lap roll, leaving the lap stick in position. The lap sticks in general use heretofore, have been of the type shown in Patent No. 355,508, issued on January 4, 1887. This type of lap stick has a cast iron handle riveted thereon and this handle very often would break, necessitating another handle being placed thereon. When a lap roll is removed from a picker, for example, the lap rolls are stood on end with the head of lap pin being disposed downwardly next to the floor or container in which the lap roll is placed. Very often it happens that the cast iron head of the lap pin when placed upon the floor with undue force, will crack and in subsequent operations this cracked cast iron handle would become separated from the lap stick and would cause the lap roll to creep into the processing machinery and sometimes results in destruction or serious damage to the machine for processing the fibres, such as, for example, the broken lap stick entering the feeder or licker-in of a card or by passing through the fluted feed rolls of the carding machine.

I have devised a simple and yet very efficient lap stick which remedies all of the above-named defects of the lap stick heretofore in use. I provide a one-piece lap stick formed of an iron rod which is bendable and which iron rod has one end thereof bent into a circular portion whose plane is disposed at right angles to the longitudinal center of the lap stick. This provides an integral handle member of the same material as the lap stick, which handle will not break and become separated from the lap stick, and therefore, provides a lap stick having a much longer

life than the old type heretofore employed and one which makes it practically impossible for any damage to occur to the machinery due to the breakage of the lap stick.

It is therefore, an object of this invention to provide a lap stick formed of a bendable iron rod having one end thereof bent into a circular handle portion disposed at right angles to the main body of the lap stick. 5

Some of the objects of the invention having been stated, other objects will appear as the description proceeds when taken in connection with the accompanying drawing in which:—

Figure 1 is an isometric view of my lap stick with the central portion thereof broken away; 15

Figure 2 is an end view of the lap stick;

Figure 3 is a view of an intermediate picker showing my lap stick in use thereon;

Figure 4 is a top plan view of Figure 3;

Figure 5 is a longitudinal sectional view 20 through a lap roll and lap pin and showing my lap stick in position;

Figure 6 is a view of the right-hand end of Figure 5 but showing the position of the lap stick as the lap pin is being removed from the lap roll. 25

Referring more specifically to the drawing, the numeral 10 indicates the lap stick proper which is bent as at 11, at right angles and after being bent outwardly a suitable distance is then bent laterally and formed into a complete circle forming a handle member 12. The lap stick is usually inserted in a lap pin 13 disposed with a lap roll 14. The lap roll is formed on a picker and is later employed in intermediate and finisher pickers, such as shown by reference character 15. 30

In one process pickers, of course, the fibres are passed from the breaker to a series of pickers to the finisher picker where the lap roll is formed, but in other forms of pickers the breaker lapper forms the lap rolls on the lap pin and then they are transferred to the intermediate picker as shown in Figure 3. This intermediate picker has an endless chain 16 for feeding the laps from the lap rolls 14. It will be seen in Figures 3 and 4 that the lap sticks 10 rest behind the standards 17 and the lap stick is usually much longer than the lap width and projects laterally from one side and the handle member 12 serves as a guide with relation to standard 17 on one side so that creeping of the lap stick from the lap roll is avoided. 40 When the lap roll is formed on the picker and is transferred to other machines such as another intermediate or a finisher picker or into a carding machine from the finisher picker only the lap stick remains. The lap pin is removed from 50 45 55

the lap roll as shown in Figure 6, leaving the lap stick to serve as the guiding means and handling means for the lap roll.

It is seen that in any of the above-described machinery that should the handle portion become separated this would allow a creeping away from the observer in Figures 3 and 4 and would allow the lap roll along with the broken lap stick to be carried forward into the beater 20 of the intermediate picker in Figures 3 and 4, doing serious damage if not irreparable injury to the beater. The same damage might occur in a carding machine as previously explained.

It is therefore seen that I have provided an integral one-piece lap stick formed of a relatively non-breakable material so that the probability

of breakage and resultant damage to the machine is avoided.

In the drawing and specification there has been set forth a preferred embodiment of the invention and although specific terms are employed, they are used in a generic and descriptive sense only, and not for purposes of limitation, the scope of the invention being set forth in the appended claim.

I claim:

A lap stick formed from a rod or iron having one end bent laterally at right angles to the rod and then bent into a circular portion occupying a plane at right angles to the longitudinal center of the rod.

JAMES R. WILSON.
